UNITED STATES PATENT OFFICE

173,322

CAKE PAN

Kenneth A. Patrick, Bethesda, Md.

Application February 5, 1954, Serial No. 28,871

Term of patent 14 years

(Cl. D44—1)

To all whom it may concern:

Be it known that I, Kenneth A. Patrick, a citizen of the United States of America, residing at Bethesda, in the county of Montgomery, State of Maryland, have invented a new, original, and ornamental Design for a Cake Pan, of which the following is a specification, reference being had to the accompanying drawing, forming a part hereof.

The figure on the drawing is a front perspective view of a cake pan showing my new design.

I claim:

The ornamental design for a cake pan, as shown.
